No. 13,081

UNITED STATES PATENT OFFICE.

JOHN GLEN, OF BROOKLYN, NEW YORK.

DESIGN FOR A PRINTED FABRIC.

SPECIFICATION forming part of Design No. 13,081, dated July 25, 1882.

Application filed May 18, 1882. Term of patent 3½ years.

To all whom it may concern:

Be it known that I, JOHN GLEN, of Brooklyn, in the county of Kings and State of New York, have invented a new and original Design for Printed Fabrics; and I do hereby declare that the following specification, taken in connection with the accompanying illustration, forming a part of the same, is a full, clear, and exact description thereof.

10 My design relates particularly to printed fabrics known as "calicoes," although it is equally applicable to silks, woolens, and other fabrics, either printed or woven.

It consists in the representation of birds 15 and branches of trees or shrubs, as will hereinafter appear.

Referring to the illustration, A A' represent a pair of birds resting upon a branch, B, of a tree or shrub. C C' represent another pair of 20 birds resting upon another branch, D. As shown in the illustration, there are combined with said birds and branches vines E, bearing

leaves and flowers, the said vines being different in color from the branches; but the vines may be omitted, if desired.

The fabric may be produced in any preferred variety or combination of colors for obtaining a desired effect, the characteristic feature of the design being birds in pairs resting upon branches, and repeated upon the ground of the 30 fabric to form the pattern.

What I claim, and desire to secure by Letters Patent, is—

1. The design for printed or other fabrics, consisting of birds in pairs resting upon 35 branches, substantially as set forth.

2. The design for printed or other fabrics, consisting of birds in pairs resting upon branches, and vines bearing leaves and flowers, substantially as shown and described.

JOHN GLEN.
